UNITED STATES PATENT OFFICE.

THOMAS H. KANE, OF YOUNGSTOWN, OHIO, ASSIGNOR TO TRUSSSED CONCRETE STEEL COMPANY, OF DETROIT, MICHIGAN, A CORPORATION OF MICHIGAN.

HINGE FOR CONTINUOUS SASHES.

1,269,939.

Specification of Letters Patent. Patented June 18, 1918.

Application filed November 26, 1917. Serial No. 204,068.

To all whom it may concern:

Be it known that I, THOMAS H. KANE, a citizen of the United States, and residing at Youngstown, in the county of Mahoning and State of Ohio, have invented new and Improved Hinges for Continuous Sashes, of which the following is a specification.

This invention relates to continuous window sashes which are supported along their upper edges so that they can be swung out for purposes of ventilation, and particularly to the supporting devices for such sashes, and its object is to provide hinges for sashes of this character which will be simple in construction, rigid and practically indestructible, and which will substantially prevent the passage of rain between the casing and sash.

This invention consists of a supporting member, secured to or forming part of the upper horizontal part of a window casing, and having its lower edge turned up to form a seat or bearing, and a down-turned flange on and parallel to the upper edge of the sash and extending into said seat or bearing so that the weight of the sash may be carried by the supporting member.

In the accompanying drawing, Figure 1 is a perspective of a sky-light provided with a sash supported by my improved hinge. Fig. 2 is a perspective of details of the sash structure. Fig. 3 is a perspective showing a clip to hold glass in position on a vertical member of the sash. Fig. 4 is a vertical section of sash supporting means.

Similar reference characters refer to like parts throughout the several views.

The sash shown in the drawing of this application may be supported at substantially any desired inclination and may be of substantially any desired construction. The bottom member of the sash is a rolled bar consisting of the parts 1, 2, 3, 4 and 5, the angles between the parts 1 and 2, 2 and 3, 45 and 3 and 4 each being of ninety degrees.

The free edge of the part 5 extends inwardly from the part 4 so as to engage the outer face of the window sill 6. The edge may be bent to form a close fit along the entire length of the sill after the sash is in position.

The upright members are shown to be angle bars at the ends of the sash and T bars intermediate the ends. The angle bars have legs 7 parallel to the plane of the sash

against which the window panes are held, and the legs 8 at right angles to this plane. The T bars have webs 9 and flanges 10. The outer faces of these flanges and of the legs 7 and of the part 2 of the lower bar are in 60 the same plane.

The top member of the sash is a channel bar having a web 12 and flanges 13 and 14. The inner face of the flange 13 is flush with the outer face of the flanges 10 and legs 7, 65 and serves to support the upper edges of the panes A. The upright and longitudinal members of the sash may be secured together in any desired manner, welding by means of the electric arc or blow-pipe preferred. The flange 14 constitutes a pivot for the sash and extends parallel to the plane of the sash.

The supporting member for the sash comprises a body portion 15 and upturned edge 75 16 forming a rounded seat or bearing for the pivot edge of the flange 14 of the top bar of the sash. This supporting member may be secured to the upper member or lintel 17 of the window casing in any desired manner, the lintel in this case being an angle bar. The supporting member and the longitudinal pivot 14 resting thereon are so proportioned that continuous and substantially air-tight contact is had between them. The sash may be made continuous for lengths of several hundred feet or more, and may be swung out at any desired angle. Entrance of rain or snow is impossible between the pivot and its seat at all times.

The panes A of glass may be held in position by any desired means, clips 19 and 20 and putty 21 being indicated. After the sash has been positioned, small stay-clips 22 are secured to the upright members of the sash in such a manner as to contact with the outer face of the bend in the supporting member and thus prevent the pivot of the sash from moving up off its seat under any circumstances.

The proportions of the parts and the details of construction of the window casing and sash may be varied by those skilled in the art to meet the various requirements of builders without departing from the spirit 105 of my invention as set forth in the following claims.

I claim:

1. The combination of a window sash having a downwardly turned flange at its

upper edge to constitute a pivot for the sash, and a supporting member for the sash having a bearing for the pivot constituted by an upturned lip to position the flange on 5 the sash.

2. The combination of a window sash whose upper member comprises a laterally projecting web and a downwardly extending flange at the outer edge of the web constituting a longitudinal pivot, and a longitudinally extending bearing member to receive said flange to support the sash. 10

3. The combination of a window sash and a longitudinal pivot secured thereto parallel 15 to the plane of the sash and along the upper edge of the sash, and a supporting member for said sash connected to the window casing along the upper transverse member thereof and constituting a longitudinal bearing for said pivot whereon said sash 20 may swing.

4. The combination of a window sash having a channel bar as its upper longitudi-

nal member, one flange of said bar constituting the pivot for the sash, and an angle 25 bar rigidly supported along the top of the window opening to constitute a longitudinal bearing for said pivot and whereon said sash may swing.

5. The combination of a window sash 30 comprising upper and lower longitudinal members and transverse members connecting them, the upper member consisting of a channel bar having a down-turned flange constituting the pivot for the sash, an angle 35 bar rigidly supported along the top of the window opening and provided with an upturned portion to constitute a longitudinal bearing for said pivot and whereon said sash may swing, and projections secured to 40 the transverse members of the sash near said pivot and adapted to engage the bearing to prevent the pivot from being lifted out of the bearing.

THOMAS H. KANE.
